United States Patent Office

Des. 180,483
Patented June 18, 1957

180,483

EARRING

David E. Hamm, Portland, Oreg.

Application November 30, 1956, Serial No. 44,002

Term of patent 7 years

(Cl. D45—9)

FIG. 1

FIG. 2

Fig. 1 is a top plan view of an earring embodying my design; and

Fig. 2 is a side elevational view of an earring embodying my design.

The dominant features of the design reside in the portion of the drawing shown in full lines.

I claim:

The ornamental design for an earring, as shown and described.
